Primary Examiner — Kimberly Barnes(74) *Attorney, Agent, or Firm* — Finch & Maloney PLLC(57) **CLAIM**

The ornamental design for a helmet, as shown and described.

DESCRIPTION

FIG. 1 is a front, side and top perspective view of a helmet showing our new design;

FIG. 2 is front elevational view thereof;

FIG. 3 is a rear elevational view thereof;

FIG. 4 is a right-side elevational view thereof; and,

FIG. 5 is a top plan view thereof.

Broken lines in the drawings are for the purpose of illustrating environmental structure and form no part of the claimed design.
